To all whom it may concern:

Be it known that I, Jacques Martial, a citizen of the United States and resident of the city, county, and State of New York, have invented a new, original, and ornamental Design for a Cabinet for Dispensing Articles, of which the following is a specification, reference being had to the accompanying drawing, forming part thereof.

Figure 1 is a perspective view of a cabinet for dispensing articles showing my new design, the door to one of the compartments being open.

Figure 2 is an end view thereof on a reduced scale.

The side and end of the cabinet opposite the side and ends shown in the figures present substantially the same appearance as the side and end shown.

The dominant feature of the design resides in the portion shown in full lines in the drawing.

I claim:

The ornamental design for a cabinet for dispensing articles, substantially as shown and described.
